UNITED STATES PATENT OFFICE.

BRYAN P. JOYCE, OF WASHINGTON, DISTRICT OF COLUMBIA.

GUN CARRIAGE.

Application filed December 5, 1921. Serial No. 520,132.

(FILED UNDER THE ACT OF MARCH 3, 1883, 22 STAT. L., 625.)

To all whom it may concern:

Be it known that I, BRYAN P. JOYCE, a citizen of the United States, and a resident of Washington, District of Columbia, have 5 invented an Improvement in Gun Carriages, of which the following is a specification.

The invention described herein may be used by the Government, or any of its officers or employees in prosecution of work 10 for the Government, or by any other person in the United States, without payment to me of any royalty thereon.

The subject of this invention is a gun carriage and the invention relates more 15 specifically to means for hanging the carriage from its axle.

In the construction of gun carriages it is desirable that the structure be of such a nature that the carriage may travel over 20 rough ground without injurious shocks and strain and that the structure may be rendered comparatively rigid and free from vibration when the gun is in action.

The present invention is devised for the 25 purpose of accomplishing these results by providing resilient means for hanging the carriage from its axle and, also, means for quickly supplying a rigid connection between the carriage and axle when the gun 30 goes into action.

With these and other objects in view, which will appear as the description proceeds, the invention resides in the novel arrangement and combination of parts and in 35 the details of construction hereinafter described and claimed, it being understood that changes in the precise embodiment of the invention herein disclosed may be made within the scope of what is claimed without departing from the spirit of the invention.

In the accompanying drawings Fig. 1 is a plan view of the bottom carriage and axle constructed in accordance with the invention, the resilient connection shown in traveling position;

Fig. 2 is an enlarged detailed sectional view taken on the line 2-2 of Fig. 1;

Fig. 3 is a front elevation, the right hand 50 resilient connection shown in firing position;

Fig. 4 is an enlarged view in longitudinal section of a resilient connection; and

Fig. 5 is a view in elevation of the same,

Referring to the drawings by numerals 55 of reference:

The bottom carriage of a gun carriage is shown at 1 and in this carriage is housed the axle 2, which is resiliently connected thereto.

A convenient form of resilient connection is shown herein and comprises a coiled spring 3, housed in a tubular casing 4, which casing is formed with an apertured head at one end and conveniently closed at 65 the other end by a ring 5 screw threaded into an end of the casing and itself threaded to receive the threads of the cap 6, which cap may be provided with an extension or rib 7 apertured to permit lubricant to be 70 supplied to the interior of the casing 4, the aperture normally closed by a plug 8. For the purpose of retaining the cap (not shown) in place a latch 9 is secured in a slot formed in the rib 7 by means of pins 75 10, the latch also extending into grooves formed in the screw plug 5 and casing 4.

A plunger 12 is housed in the casing 4 and is formed with a collar 13 adjacent one end, the collar adapted to pass through the 80 aperture in the head of the casing, and with a head 14 at its other end which head slides within the ring 5 and cap 6. The ends of the coiled spring 3 are seated in cups 15-15 interposed between the cups and the head 85 of the casing 4 and the ring 5 are washers 16-16, the purpose of which is to prevent pounding of metal on metal.

The plunger 12 has formed at the extending end thereof an eye 17 which is pivoted 90 between ears 18, formed on the carriage 1, by means of a pivot pin 19. Encircling the casing 4, and preferably connected thereto by screwed threads as shown, is a hand 20 carrying trunnions 21 and formed with a 95 lug 22 to which is pivotally connected a hasp 23. The trunnions 21 normally rest in sockets formed in members 24, which are suitably mounted on the axle 2, and are held in place therein by the hooked arms 25 100 mounted on the squared ends of shaft 26, on the forward end of which shaft is also mounted a crank arm 27 provided at its free end with a handle 28, which handle is in the form of a resilient latch to engage the 105 spaced apart apertures 29 to hold the arm 25 in either of two positions.

The carriage 1 has alining apertures 30

formed in the front and rear plates of the axle housing which apertures may be alined with an aperture 31 formed in the axle. The aperture in the front plate is closed by a door 32 hinged at 33 and normally held in close position by a latch 34. Apertures 35 are also formed in the front plate and in substantial alinement with sockets or recesses 36 formed in the axle. By this construction the axle may be rigidly connected to the carriage in the following manner:

The door 32 is open and pinch bars inserted through the apertures 35 and into the sockets 36 and the position of the carriage with relation to the axle thus adjusted, through the pinch bars as levers, to bring the aperture 31 into alinement with the apertures 30. When the apertures are thus alined a pin 37 is inserted into the apertures 30 and 31 thus locking the axle 2 rigidly to the carriage 1. The handle 28 is then drawn outwardly to free the catch from one hole 29 and the arm 27 swung to rotate the shaft 26 and elevate the arms 25 to free the trunnions. The arms are held in their elevated position by allowing the latch handle 28 to engage the other apertures 29. The resilient elements are then free to be swung on the pivot pin 19 to a position adjacent the sides 0 of the axle housing and may be secured in such position by lowering the hasps 23 over staples 38 carried on the top plate of the axle housing, and the hasps may be locked in engagement with the staples by means of snap hooks 39 which are conveniently secured to the top plate of the housing.

What I claim is:

1. A gun carriage, including a bottom carriage, an axle housing formed on the carriage and provided with apertures, an axle

loosely mounted in the housing and provided with an aperture and recesses alining with respective apertures of the housing, socket members formed on the axle, resilient members pivoted to the carriage, trunnions 45 carried by the resilient members and adapted to seat in the sockets of the socket members, hooked arms carried by the axle and normally holding the trunnions in position in the socket, a crank arm, for moving the hooked arms to trunnion holding or released positions, a latch for locking the crank arm in either position, and means insertible in the aperture of the carriage and axle for rigidly connecting the carriage to the axle. 50

2. A gun carriage including a bottom carriage, provided with apertures, an axle formed with an aperture adapted to aline with the apertures of the carriage, resilient connections pivoted to the carriage and detachably connected to the axle, and a pin insertible in the apertures of the carriage and axle to permit the resilient connections to be detached from the axle and to rigidly connect the carriage to the axle. 55

3. A gun carriage, including a bottom carriage, an axle, resilient connections pivoted to the carriage, means for detachably connecting the connections to the axle, and means for rigidly securing the axle to the carriage to permit the resilient connections to be detached from the axle. 60

4. A gun carriage, an axle, resilient connectors pivoted to the carriage and detachably fastened to the axle, means for rigidly securing the axle to the carriage to permit the connectors to be detached therefrom and means for holding the connectors in detached position. 65

BRYAN P. JOYCE.
